UNITED STATES PATENT OFFICE.

EDWARD N. JACOBI, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

LOCK.

Application filed October 9, 1920. Serial No. 415,741.

To all whom it may concern:

Be it known that I, EDWARD N. JACOBI, a citizen of the United States, and resident of Milwaukee, Milwaukee County, Wisconsin, have invented new and useful Improvements in Locks, of which the following is a description, reference being had to the accompanying drawings, which are a part of this specification.

10 This invention relates to locks of the type used for locking tool boxes of automobiles wherein a knob-controlled latch may be locked by a removable key to prevent unauthorized access to the tool box. The invention, however, is capable of various uses and is not to be limited to any particular purpose.

20 An object of the invention is to simplify the construction and make it inexpensive to manufacture though durable and efficient and with a wide range of key changes.

With the above and other objects in view the invention consists in the lock as herein claimed and all equivalents.

25 Referring to the accompanying drawings in which like characters of reference indicate the same parts in different views:

Fig. 1 is a front view of a lock constructed in accordance with this invention;

30 Fig. 2 is an edge view thereof;

Fig. 3 is a front view with parts sectioned;

Fig. 4 is a central sectional view;

35 Fig. 5 is a rear view of the cover plate removed and inverted;

Fig. 6 is a view of the knob or thimble;

Fig. 7 is a perspective view of the lock sleeve; and,

40 Fig. 8 is a sectional view of the lock barrel with the key in place.

In these drawings 10 indicates a lock case of sheet metal bent to shape as usual and 11 is the cover plate therefor having the usual spotting lugs 12 fitting in notches in the edge of the lock case. The lock case and cover plate are held together by rivet posts 13 upset at both ends. A sliding lock bolt 14 fits in an opening in one end of the lock case and is guided by a slotted wing 15 riding on a pin 16. Another wing is recessed to form a spring seat 17 for a coil spring 18 which is confined within it at one end and bears on the end of the lock case at the

other end where the lock case is provided with an indentation 19 forming a projection 55 on the interior thereof for holding the spring centered. The upper portion 20 of the spring seat 17 is of sufficient width to bear against the bottom of the lock case and the cover plate to steady the lock bolt. 60

A sheet metal cylindrical knob 21 with an inwardly turned flange at one end and an outwardly turned flange at the other end fits within an opening of the cover plate. The outwardly turned flange of the knob 21 is confined between the cover plate and the attaching flange 22 of a cylindrical lock sleeve 23. The cylindrical lock sleeve projects within the knob 21 while the attaching flange 22 is connected by rivets 24 to 70 the cover plate. The flange of the knob 21 is not entirely enclosed by the attaching flange 22 and at its exposed portion it is provided with a projecting finger 25 which engages a recess 26 in the lock bolt to cause 75 the withdrawal of the lock bolt against the pressure of its spring when the knob is turned.

80 A lock cylinder 27 fits within the lock sleeve 23 with its shoulder 27' against an inturned flange at the end of the sleeve and its outer end projects through the end of the knob 21 while its inner end bears against the flat surface of the lock bolt 14. A number of tumbler slides 28 fit within the lock barrel transversely thereof and are aligned flush with the surface of the lock barrel by the serrated edges of a key 29 when it is inserted in the longitudinally extending key way 30. When the key is withdrawn, however, these tumbler slides 28 are projected into opposite openings 31 of the lock sleeve 23 so that the lock barrel is incapable of being turned. The key not only withdraws the tumbler slides but it serves as a handle by means of which the lock barrel may be turned and so cause an eccentrically positioned projecting pin 32 on the end of the lock barrel to be moved from one position to another. In one position the pin 32, as shown by full lines in Fig. 3, stands in the path of the lock bolt 14 so as to prevent its withdrawal, but in the other position, as shown by dotted lines in said figure, it is removed from the path of the lock bolt and the latter is free to be with- 90 95 100 105

drawn either by the cam action of its beveled projecting end on engaging the strike plate, or by the turning of the knob. As the tumbler slides 28 may project within the slots 31 of the lock sleeve in either of these two positions, it is obvious that the key may be withdrawn either when the bolt is locked or when it is unlocked.

Registering openings 33 in the lock case 10 and cover plate are to receive attaching screws or rivets, not shown, for securing the lock in place.

In operation the lock bolt may act as a latch to yield against the pressure of its spring when the lock barrel is in position to place the pin 32, as shown by dotted lines in Fig. 3. This yielding movement of the lock bolt may be occasioned by the cam action of the beveled end thereof on closing 15 the door to which the lock is attached or it may be caused by the turning of the knob 20 so that the finger 25 thereof bears against the shoulder or notch 26. When, however, the lock barrel is locked in its other position with the pin 32 in the position shown in Figs. 3 and 4, the lock bolt cannot be withdrawn by either means. The tumbler slides 25 by projecting in the openings 31 serve to lock the lock barrel in either of these two 30 positions and require the presence of the key in order to withdraw them to a position in which the lock barrel may be moved. The key also serves as a handle for moving the lock barrel when it is unlocked.

35 The lock construction is composed of few parts inexpensive to manufacture and easy to assemble and is not likely to wear or get out of order. It requires no friction means for holding the lock barrel in position to 40 receive the key for the lock barrel is locked in that position whenever the key is removed. The lock mechanism being contained within the knob relieves the lock case of small parts and permits of the use of a 45 coil spring and heavy bolt construction.

What I claim as new and desire to secure by Letters Patent is:

1. In a lock, a lock bolt, a rotatably mounted knob for moving the lock bolt, and 50 a key-controlled lock barrel within the knob having a projection on its end eccentric

thereto for blocking the movements of the lock bolt.

2. In a lock, a lock bolt, a rotatable knob 55 for moving the lock bolt, a stationary lock sleeve within the knob, a key-controlled lock barrel rotatably mounted within the lock sleeve and engageable therewith, and an eccentric projection on the lock barrel for blocking the lock bolt in a locking position 60 of the lock barrel.

3. In a lock, a lock case, a knob rotatably mounted therein, a lock barrel contained within the knob and adapted to receive a key, tumblers within the lock barrel positioned by the key, a lock sleeve between the barrel and knob engaged by the tumblers when the key is removed, a lock bolt in the lock case engaged and moved by the knob, and a projection on the lock barrel standing in the path of the lock bolt in a position 65 of the lock barrel in which the key may be removed.

4. In a lock, a lock case, a cover plate fitted thereto, a sliding lock bolt within the lock case, a knob rotatably mounted in the cover plate and provided with a finger engaging the lock bolt for moving it, a lock sleeve within the knob secured to the cover plate and provided with openings, a lock 75 barrel rotatably mounted in the lock sleeve and the knob, key controlled tumbler slides in the lock barrel adapted to engage the openings of the lock sleeve, and a projection on the lock barrel adapted to block the lock bolt 80 in a locking position of the lock barrel.

5. In a lock, a lock case, a cover plate therefor, a knob rotatably mounted in the cover plate, a lock sleeve riveted to the cover plate and having a cylindrical portion 90 within the knob provided with openings, a lock barrel rotatably mounted in the lock sleeve and the knob, key-controlled tumbler slides in the lock barrel adapted to engage the openings of the sleeve, a spring-pressed lock 95 bolt, a finger on the knob engaging the lock bolt for moving it, and a pin projecting from the lock barrel and standing in the path of the lock bolt in a locking position of the lock barrel.

In testimony whereof, I affix my signature.
EDWARD N. JACOBI.
